DISPLAY METHOD AND DISPLAY DEVICE

The present application is based on, and claims priority from JP Application Serial Number 2022-157658, filed Sep. 30, 2022, the disclosure of which is hereby incorporated by reference herein in its entirety.

BACKGROUND

1. Technical Field

The present disclosure relates to a display method and a display device.

2. Related Art

A display device that displays a user setting image is known. A display device described in JP-A-2007-140180 takes in an image signal inputted from an external device. The display device determines the type of the inputted image signal. When unable to determine the type of the inputted image signal, the display device generates a user setting image. The display device displays the generated user setting image. The display device displays the user setting image and thus prompts a user to update setting data. Meanwhile, when able to determine the type of the inputted image signal, the display device does not display the user setting image.

Conditions for displaying the user setting image are limited. Therefore, the user setting image may not necessarily be displayed to a user who is not very familiar with user settings.

SUMMARY

According to an aspect of the present disclosure, a display method includes: presetting a display mode for displaying a setting screen; accepting an input of an image signal from an external device; and displaying the setting screen, when the image signal is inputted and it is determined that the display mode is in operation.

According to another aspect of the present disclosure, a display device includes: an interface circuit that accepts an input of an image signal outputted from an external device; one or a plurality of processors that execute presetting a display mode for displaying a setting screen, and displaying the setting screen, when the image signal is inputted to the interface circuit and it is determined that the display mode is in operation; and a display panel that displays the setting screen under control of the one or plurality of processors.

BRIEF DESCRIPTION OF THE DRAWINGS

FIG. 1 shows a schematic configuration of a projection system.

FIG. 2 shows a block configuration of the projection system.

FIG. 3 shows a schematic configuration of a projection unit.

FIG. 4 is a flowchart related to a display method for a projector.

FIG. 5 shows a schematic configuration of a scene setting screen.

FIG. 6 shows a schematic configuration of a detailed setting screen.

FIG. 7 shows a schematic configuration of the detailed setting screen.

FIG. 8 shows a schematic configuration of the scene setting screen.

FIG. 9 is a flowchart related to a display method for the projector.

FIG. 10 is a flowchart related to a display method for the projector.

DESCRIPTION OF EMBODIMENTS

10 FIG. 1 shows a schematic configuration of a projection system 1. The projection system 1 has a projector 10 and an image providing device 50. The projector 10 projects a projection image PG onto a projection surface SC. The projection system 1 shown in FIG. 1 has one image providing device 50 but is not limited to this configuration. A plurality of image providing devices 50 may be connected to the projector 10.

The projection surface SC displays the projection image PG projected from the projector 10. The projection surface SC shown in FIG. 1 is formed of a screen but is not limited to this configuration. The projection surface SC may be an indoor wall, a ceiling, an external wall of a building, or the like. The projection surface shape of the projection surface SC is not limited to a planar shape. The projection surface SC may be a curved surface, a concave-convex surface, or a three-dimensionally shaped surface such as a spherical surface.

20 The projector 10 is arranged at a position facing the projection surface SC. The projector 10 is communicatively connected to the image providing device 50. The projector 10 may also be communicatively connected to a control device that is different from the image providing device 50. The projector 10 receives image data from the image providing device 50. The projector 10 projects the projection image PG onto the projection surface SC, based on the image data. The projector 10 may also project the projection image PG onto the projection surface SC, based on internally stored display data. The projector 10 is equivalent to an example of a display device.

30 40 The projector 10 has an operation panel 11. The operation panel 11 is operated by a user. The user makes an operation input to the operation panel 11 and thus configures various settings of the projector 10. The operation panel 11 has a plurality of input buttons 13.

45 50 The image providing device 50 is communicatively connected to the projector 10. The image providing device 50 transmits image data to the projector 10. The image providing device 50 may have a function of adjusting the image shape of the projection image PG projected onto the projection surface SC by the projector 10. The image providing device 50 is a tablet terminal, a smartphone, a mobile computer, a desktop computer, or the like. The image providing device 50 is equivalent to an example of an external device.

55 60 FIG. 2 shows the block configuration of the projection system 1. FIG. 2 shows the block configuration of the projector 10 and the block configuration of the image providing device 50. The projector 10 is communicatively connected to the image providing device 50 via a wire or a wirelessly.

The projector 10 has the operation panel 11, a communication interface 15, a memory 17, a control unit 21, and a projection unit 30. The image providing device 50 has a storage unit 51, a data processing unit 55, and a communication unit 57.

65 The operation panel 11 has a plurality of input buttons 13. In an example, the plurality of input buttons 13 include a

menu button, a return button, a decision button, a selection button, an adjustment button, an initial value button, and the like. The user suitably selects a desired input button 13 from among the plurality of input buttons 13 and makes an operation input to the input button 13. The user may use a remote controller, not illustrated, instead of the operation panel 11. The user makes an operation input, using the remote controller. The remote controller has a plurality of input buttons similarly to the operation panel 11. In other words, the operation panel 11 or the remote controller accepts an operation from the user.

The communication interface 15 is an interface circuit for communicatively connecting to the image providing device 50. The communication interface 15 connects to the image providing device 50 via a wire or wirelessly in conformity with a predetermined communication protocol. The communication interface 15 includes a wired connector and a wireless communication port. The wired connector is an HDMI (High-Definition Multimedia Interface) connector, a USB (Universal Serial Bus) connector, a LAN (local area network) connector, or the like. The wireless communication port is a Wi-Fi communication port, a Bluetooth communication port, or the like. HDMI, Wi-Fi, and Bluetooth are registered trademarks. The communication interface 15 accepts an input of image data, device information, and the like from the image providing device 50. The communication interface 15 may receive setting data or the like of the projector 10 from the image providing device 50. The communication interface 15 is equivalent to an example of a reception unit. The image data is data related to an image, including still image data, dynamic image data, or the like. The image data may include audio data. The image data is equivalent to an example of an image signal.

The memory 17 stores image data and various program data. The memory 17 stores a control program CP to be executed by the control unit 21. The memory 17 stores the image data, the device information, and the like transmitted from the image providing device 50. The memory 17 stores various screen data and the like. The screen data is data for causing the projection unit 30 to display an operation screen such as a scene setting screen 100 or a detailed setting screen 110. The scene setting screen 100 and the detailed setting screen 110 will be described later. The memory 17 stores mode information. The mode information represents a screen display mode or a screen non-display mode. The memory 17 is formed of a ROM (read-only memory), a RAM (random-access memory) or the like. The control program CP is equivalent to an example of a program.

The memory 17 stores external device information 19. The external device information 19 is device information about an external device communicatively connected via the communication interface 15. The external device information 19 includes device-specific information 53. The device-specific information 53 will be described later. The memory 17 stores the device-specific information 53 or the like in an inputted data format or in a processed data format. The external device information 19 is equivalent to an example of identification information.

The memory 17 stores an initial set value group. The initial set value group is set data including an initial set value corresponding to a setting item. The initial set value group is set corresponding to a scene type. The scene type is the content type of the projection image PG projected on the projection surface SC, based on the image data. The scene type includes game, movie, presentation, and the like. The initial set value group is stored for each scene type. The memory 17 stores a plurality of initial set value groups.

When the initial set value group is modified, the memory 17 stores the modified initial set value group, as set value group. The plurality of initial set value groups include a standard set value group. The standard set value group is set data including a standard value of each setting item. The standard value of each setting item is a value predetermined by the manufacturer of the projector 10. The standard set value group may be stored as a common set value group corresponding to a plurality of scene types.

The control unit 21 is a controller that controls the projector 10. In an example, the control unit 21 is a processor having a CPU (central processing unit). The control unit 21 is formed of one or a plurality of processors. The control unit 21 may have a semiconductor memory such as a ROM or a RAM. The semiconductor memory functions as a work area of the control unit 21. The control unit 21 executes the control program CP stored in the memory 17 and thus functions as an OSD control unit 23 and an image control unit 25. The control unit 21 is equivalent to an example of a display control unit.

The OSD control unit 23 performs display control of various screens projected on the projection surface SC. OSD is an abbreviation of on-screen display. The OSD control unit 23 is a functional unit that operates when the control unit 21 executes the control program CP. The OSD control unit 23 controls whether or not to display an operation screen such as the scene setting screen 100. The OSD control unit 23 controls the display content of the operation screen such as the scene setting screen 100. The OSD control unit 23 is equivalent to an example of the display control unit.

The OSD control unit 23 controls whether or not to display the scene setting screen 100. The OSD control unit 23 can set mode information. The mode information represents a screen display mode or a screen non-display mode. The OSD control unit 23 can execute a switching setting to switch the mode information from the screen display mode to the screen non-display mode or from the screen non-display mode to the screen display mode. The OSD control unit 23 causes the memory 17 to store the screen display mode or the screen non-display mode, which is the mode information. The memory 17 stores the mode information.

The screen display mode is a mode for displaying the scene setting screen 100 when image data is inputted from the image providing device 50. The screen display mode is equivalent to an example of a display mode. The scene setting screen 100 is equivalent to an example of a setting screen. The screen display mode is preset as an initial setting at the time of shipment from the plant or when the projector 10 is reset, or the like. The screen display mode may be set by a manager or the like of the projector 10 via a management screen of the projector 10. When the manager or the like inputs a setting to switch from the screen non-display mode to the screen display mode on the management screen, the OSD control unit 23 executes the switching setting to switch from the screen non-display mode to the screen display mode.

The screen non-display mode is a mode for not displaying the scene setting screen 100 when image data is inputted from the image providing device 50. The screen non-display mode is equivalent to an example of a non-display mode. The user of the projector 10 can set the screen non-display mode via the scene setting screen 100 when the scene setting screen 100 is displayed. When the user inputs a setting to switch from the screen display mode to the screen non-display mode on the scene setting screen 100, the OSD control unit 23 executes the switching setting to switch from

the screen display mode to the screen non-display mode. On the scene setting screen 100, the screen non-display mode can be set.

The OSD control unit 23 acquires the mode information stored in the memory 17, when image data is inputted from the image providing device 50. The OSD control unit 23 determines whether the mode information represents the screen display mode or not. When it is determined that the mode information represents the screen display mode, the OSD control unit 23 displays the scene setting screen 100. When it is determined that the mode information does not represent the screen display mode, the OSD control unit 23 determines that the mode information represents the screen non-display mode for not displaying the scene setting screen 100. When it is determined that the mode information represents the screen non-display mode, the OSD control unit 23 does not display the scene setting screen 100.

The OSD control unit 23 causes the projection unit 30 to project various operation screens such as the scene setting screen 100. The OSD control unit 23 reads out the screen data stored in the memory 17. The OSD control unit 23 transmits the read-out screen data to the projection unit 30 and causes the projection unit 30 to project an operation screen based on the screen data. The OSD control unit 23 causes the projection unit 30 to project the operation screen and thus to display the operation screen on the projection surface SC.

The memory 17 stores a plurality of screen data. The plurality of screen data include scene setting screen data and detailed setting screen data. The scene setting screen data is data for displaying the scene setting screen 100. The detailed setting screen data is data for displaying the detailed setting screen 110.

The image control unit 25 performs image processing on the image data acquired from the image providing device 50. The image control unit 25 corrects the image data, based on a set value group. The set value group is set, based on input data accepted via the scene setting screen 100 or the detailed setting screen 110. The set value group is set data including set values corresponding to a plurality of setting items. The set value group is stored in the memory 17. The image control unit 25 reads out the set value group from the memory 17. Details of the set value group will be described later. The image control unit 25 generates corrected image data, which is the image data that is corrected. The image control unit 25 transmits the corrected image data thus generated, to the projection unit 30.

The projection unit 30 projects the projection image PG onto the projection surface SC under the control of the control unit 21. The projection unit 30 projects the projection image PG based on the corrected image data onto the projection surface SC. The projection unit 30 projects various operation screens onto the projection surface SC, based on the screen data. The various operation screens include the scene setting screen 100, the detailed setting screen 110, and the like. The various operation screens are an example of the projection image PG. Details of the projection unit 30 will be described later. The projection unit 30 is equivalent to an example of a display unit.

The image providing device 50 outputs image data to the projector 10. The image providing device 50 is connected to the communication interface 15 of the projector 10. The image providing device 50 has the storage unit 51, the data processing unit 55, and the communication unit 57.

The storage unit 51 stores various image data, device information, and the like. The storage unit 51 stores various information about the image providing device 50 including

the device-specific information 53, as the device information. The device-specific information 53 is information that identifies the image providing device 50. The device-specific information 53 is the IP address, the MAC address, the product name, the serial number, and the like. The device-specific information 53 is equivalent to an example of an identification signal. The storage unit 51 is formed of a ROM, a RAM or the like. The storage unit 51 may be formed of a magnetic recording device such as an HDD (hard disk drive).

The data processing unit 55 is an image processing controller that generates various image data. The data processing unit 55 causes various applications to operate and thus generates image data. The data processing unit 55 transmits the generated image data to the communication unit 57. The data processing unit 55 may transmit the generated image data to the storage unit 51 and may cause the storage unit 51 to store the image data. The data processing unit 55 is formed of one or a plurality of image processing processors.

The communication unit 57 is a communication circuit that communicatively connects to the projector 10. The communication unit 57 connects to the projector 10 via a wire or wirelessly in conformity with a predetermined communication protocol. The communication unit 57 communicatively connects to the communication interface 15. The communication unit 57 includes a wired connector and a wireless communication port. The wired connector is an HDMI connector, a USB connector, a LAN connector or the like. The wireless communication port is a Wi-Fi communication port, a Bluetooth communication port or the like. The communication unit 57 transmits image data to the projector 10. The communication unit 57 may receive various notification data or the like from the projector 10.

When outputting image data to the communication interface 15, the communication unit 57 may add the device-specific information 53 to the image data. When communicatively connected to the communication interface 15, the communication unit 57 may output the device-specific information 53 to the communication interface 15.

FIG. 3 shows a schematic configuration of the projection unit 30. FIG. 3 shows an example of the projection unit 30. The projection unit 30 has a light source 31, three liquid crystal light valves 33, a light valve drive unit 35, and a projection lens 37.

The light source 31 emits light to the liquid crystal light valve 33. The light source 31 has a light source unit 31a, a reflector 31b, an optical integration system, not illustrated, and a color separation system, not illustrated. The light source unit 31a emits light. The light source unit 31a is formed of a xenon lamp, an ultra-high-pressure mercury lamp, an LED (light-emitting diode), or a laser light source or the like. The light source 31 emits light under the control of the control unit 21. The reflector 31b reduces the variation in the direction of emission of the light emitted from the light source unit 31a. The optical integration system reduced the variation in the luminance distribution of the light emitted from the light source 31. The light passed through the reflector 31b becomes incident on the color separation system. The color separation system separates the incident light into red, green, and blue color light components.

The liquid crystal light valve 33 modulates the light emitted from the light source 31. The liquid crystal light valve 33 modulates the light and thus generates the projection image PG. The liquid crystal light valve 33 is formed of a liquid crystal panel made up of a pair of transparent substrates and a liquid crystal encapsulated between the

substrates, or the like. The liquid crystal light valve 33 has a rectangular pixel area 33a including a plurality of pixels 33p arranged in the form of a matrix. In the liquid crystal light valve 33, a drive voltage is applied to the liquid crystal on a per pixel 33p basis. The projection unit 30 shown in FIG. 3 has three liquid crystal light valves 33. The liquid crystal light valve 33 is an example of a display panel. The projection unit 30 is configured having the liquid crystal light valve 33 but is not limited to this configuration. The projection unit 30 may be configured including one or more DMDs (digital mirror devices). In this case, the DMD is an example of the display panel.

The three liquid crystal light valves 33 are a liquid crystal light valve for red light 33R, a liquid crystal light valve for green light 33G, and a liquid crystal light valve for blue light 33B. The red color light component separated by the color separation system becomes incident on the liquid crystal light valve for red light 33R. The green color light component separated by the color separation system becomes incident on the liquid crystal light valve for green light 33G. The blue color light component separated by the color separation system becomes incident on the liquid crystal light valve for blue light 33B.

The light valve drive unit 35 applies a drive voltage to each pixel 33p, based on the image data received from the control unit 21. The light valve drive unit 35 is, for example, a control circuit. The drive voltage is supplied by a drive source, not illustrated. The light valve drive unit 35 may apply the drive voltage to each pixel 33p, based on the image data corrected by the image control unit 25. As the light valve drive unit 35 applies the drive voltage to each pixel 33p, each pixel 33p is set to a light transmittance based on the image data. The light emitted from the light source 31 is transmitted through the pixel area 33a and thus modulated. The three liquid crystal light valves 33 form color component images corresponding to the respective colors thereof.

The projection lens 37 combines together the color component images formed by the liquid crystal light valves 33 and projects the combined image in an enlarged form. The projection lens 37 projects the projection image PG onto the projection surface SC. The projection image PG is a multiple-color image formed of the color component images combined together.

First Embodiment

A first embodiment represents a display method for displaying the scene setting screen 100. In the first embodiment, a display method for displaying a first scene setting screen 100a, which is an example of the scene setting screen 100, is described. The first scene setting screen 100a will be described later.

FIG. 4 shows a flowchart related to a display method for the projector 10. FIG. 4 shows a display method for displaying the first scene setting screen 100a, which is an example of the scene setting screen 100.

In step S101, the projector 10 takes in image data inputted from the image providing device 50. The communication interface 15 of the projector 10 communicatively connects to the communication unit 57 of the image providing device 50. The communication interface 15 takes in image data inputted from the communication unit 57. The communication interface 15 outputs the image data to the OSD control unit 23 of the control unit 21. The OSD control unit 23 takes in the image data inputted thereto.

When the image data is inputted to the projector 10, the projector 10 determines in step S103 whether the mode

information represents the screen display mode or not. The mode information represents the screen display mode or the screen non-display mode. The mode information is preset before the image data is inputted. The mode information is stored in the memory 17. In initial settings, the screen display mode is preset in the projector 10. The initial settings are settings set at the time of the shipment of the projector 10 from the plant or when the projector 10 is reset.

When it is determined that the mode information represents the screen display mode, the OSD control unit 23 proceeds to step S105 (YES in step S103). When it is determined that the mode information does not represent the screen display mode, the OSD control unit 23 determines that the mode information represents the screen non-display mode. When it is determined that the mode information represents the screen non-display mode, the OSD control unit 23 proceeds to step S131 (NO in step S103).

When it is determined in step S103 that the mode information represents the screen non-display mode, the projector 10 acquires a standard set value group in step S131. The OSD control unit 23 reads out the standard set value group from the memory 17. The memory 17 stores the standard set value group in advance. The OSD control unit 23 outputs the standard set value group as a set value group to the image control unit 25. After the set value group is outputted to the image control unit 25, the projector 10 proceeds to step S115.

The screen non-display mode can be set when the scene setting screen 100 is displayed. When previous image data is inputted from the image providing device 50 before the image data is inputted from the image providing device 50, the user can set the screen non-display mode, using the scene setting screen 100.

In step S105, the projector 10 displays the first scene setting screen 100a. The OSD control unit 23 causes the projection unit 30 to project the first scene setting screen 100a, based on the scene setting screen data, and thus to display the first scene setting screen 100a on the projection surface SC. The projection unit 30 projects the first scene setting screen 100a onto the projection surface SC under the control of the OSD control unit 23.

FIG. 5 shows a schematic configuration of the scene setting screen 100. FIG. 5 shows a schematic configuration of the first scene setting screen 100a, which is an example of the scene setting screen 100. The first scene setting screen 100a shown in FIG. 5 is displayed on the projection surface SC in step S105 in FIG. 4.

The first scene setting screen 100a displays a plurality of selection icons 101. Each of the plurality of selection icons 101 can accept a selection input, which is an operation input by the user. The user makes an operation input to the input button 13 on the operation panel 11 and thus can select a selection icon 101. The plurality of selection icons 101 are a game icon 101a, a movie icon 101b, a presentation icon 101c, a multi-screen icon 101d, a common icon 101e, and an icon yet to be set 101f. The number of the selection icons 101 displayed on the first scene setting screen 100a is not limited to six. The number of the selection icons 101 may be any number equal to or greater than two. The game, movie, presentation, and multi-screen represent scene types of the projection image PG projected by the projector 10.

The game icon 101a is an icon selected by the user when the image data is a game image. When the user has determined that the data image outputted from the image providing device 50 is a game image, the user makes a selection input to the game icon 101a. As the selection input to the

game icon **101a** is accepted, the game icon **101a** is selected. The game icon **101a** is an equivalent to an example of a first item image.

The movie icon **101b** is an icon selected by the user when the image data is a movie image. When the user has determined that the data image outputted from the image providing device **50** is a movie image, the user makes a selection input to the movie icon **101b**. As the selection input to the movie icon **101b** is accepted, the movie icon **101b** is selected. The movie icon **101b** is an equivalent to an example of a second item image.

The presentation icon **101c** is an icon selected by the user when the image data is a presentation image. When the user has determined that the data image outputted from the image providing device **50** is a presentation image, the user makes a selection input to the presentation icon **101c**. As the selection input to the presentation icon **101c** is accepted, the presentation icon **101c** is selected.

The multi-screen icon **101d** is an icon selected by the user when the image data is a multi-image showing a plurality of images on the same screen. When the user has determined that the data image outputted from the image providing device **50** is a multi-image, the user makes a selection input to the multi-screen icon **101d**. As the selection input to the multi-screen icon **101d** is accepted, the multi-screen icon **101d** is selected.

The common icon **101e** is an icon selected by the user when the image data is an image that is not discriminated by the scene type. When the user has determined that the data image outputted from the image providing device **50** is an image that is not discriminated by the scene type, the user makes a selection input to the common icon **101e**. As the selection input to the common icon **101e** is accepted, the common icon **101e** is selected.

The icon yet to be set **101f** is an icon on which the manager of the projector **10** can set a scene type. The icon yet to be set **101f** can be set when the manager has configured a predetermined setting on the icon yet to be set **101f**. It is shown that the icon yet to be set **101f** cannot be selected by the user of the projector **10**.

The first scene setting screen **100a** displays a display setting field **103**. The display setting field **103** accepts a switching operation input to switch from the screen display mode to the screen non-display mode. The screen non-display mode can be set when the first scene setting screen **100a** is displayed. The display setting field **103** illustrated in FIG. 5 shows a state where no switching operation input is accepted. When the switching operation input to the display setting field **103** is accepted, the display form of the display setting field **103** is changed. In an example, a checkmark image is superimposed on the display setting field **103**. The display setting field **103** is equivalent to an example of a switching input field. The switching operation input is equivalent to an example of switching input information.

The display method includes accepting an operation to set the screen non-display mode for not displaying the first scene setting screen **100a**, when the first scene setting screen **100a** is displayed.

The screen non-display mode can be selected when image data is inputted. When image data is inputted to the projector **10**, the user can switch to the screen non-display mode for not displaying the first scene setting screen **100a**.

Referring back to FIG. 4, after displaying the first scene setting screen **100a**, the projector **10** in step **S107** accepts a selection input from the user. The user operates the input button **13** on the operation panel **11** and thus makes a selection input. A selection input to one selection icon **101**

of the plurality of selection icons **101** displayed on the first scene setting screen **100a** shown in FIG. 5 is accepted. A switching operation input by the user to the display setting field **103** may be accepted.

When the selection input to the selection icon **101** is accepted, the projector **10** in step **S109** accepts a scene type corresponding to the selection icon **101** accepted on the first scene setting screen **100a**. The OSD control unit **23** accepts the scene type corresponding to selection icon **101**. The OSD control unit **23** temporarily stores the scene type corresponding to the selection icon **101**. The OSD control unit **23** may cause the memory **17** to store the scene type corresponding to the selection icon **101**.

When the switching operation input to the display setting field **103** is accepted, the projector **10** in step **S109** switches the mode information from the screen display mode to the screen non-display mode. The OSD control unit **23** causes the memory **17** to store the screen non-display mode as the mode information, based on the switching operation input.

When no switching operation input to the display setting field **103** is accepted, the projector **10** in step **S109** does not switch the mode information from the screen display mode to the screen non-display mode. The projector **10** maintains the screen display mode. The memory **17** continues storing the screen display mode as the mode information.

The first scene setting screen **100a** has the display setting field **103** for accepting an operation to switch from the screen display mode to the screen non-display mode. In the display method, accepting the operation to set the screen non-display mode for not displaying the first scene setting screen **100a** includes: accepting a switching operation input inputted to the display setting field **103** when the first scene setting screen **100a** is displayed; and switching the screen display mode to the screen non-display mode, based on the switching operation input.

The screen non-display mode can be set when the first scene setting screen **100a** is displayed. The user can select the screen non-display mode for not displaying the first scene setting screen **100a** the next time image data is inputted from the image providing device **50**.

After storing the scene type corresponding to the selection icon **101**, the projector **10** in step **S111** displays the detailed setting screen **110**. The OSD control unit **23** transmits the detailed setting screen data to the projection unit **30**. The OSD control unit **23** causes the detailed setting screen **110** to be projected onto the projection surface **SC**, based on the detailed setting screen data. The OSD control unit **23** causes the projection unit **30** to project the detailed setting screen **110** and thus to display the detailed setting screen **110** on the projection surface **SC**.

FIG. 6 shows a schematic configuration of the detailed setting screen **110**. FIG. 6 shows a first detailed setting screen **110a**, which is an example of the detailed setting screen **110**. The first detailed setting screen **110a** is displayed when a selection input to the game icon **101a** is accepted on the first scene setting screen **100a**. The first detailed setting screen **110a** corresponds to the game icon **101a**. The first detailed setting screen **110a** is equivalent to an example of a first display setting screen.

The first detailed setting screen **110a** displays a plurality of setting icons **111**. The first detailed setting screen **110a** displays a color mode setting icon **111a**, a brightness setting icon **111b**, a contrast setting icon **111c**, a sharpness setting icon **111d**, a frame delay setting icon **111e**, an aspect setting icon **111f**, and a sound volume setting icon **111g**. The number of the setting icons **111** displayed on the detailed setting screen **110** is not limited to seven. The number of the

11

setting icons **111** may be any number equal to or greater than one. The setting icons **111** include an icon related to image adjustment. The color mode setting icon **111a**, the brightness setting icon **111b**, the contrast setting icon **111c**, the sharpness setting icon **111d**, the frame delay setting icon **111e**, and the aspect setting icon **111f** are related to image adjustment. The setting icon **111** corresponds a setting item. The color mode, brightness, contrast, sharpness, frame delay, aspect, and sound volume are setting items.

The control unit **21** stores an initial set value of the setting item corresponding to the setting icon **111** displayed on the detailed setting screen **110**. When a plurality of setting icons **111** are displayed, the control unit **21** reads out an initial set value group including the initial set value of the setting item corresponding to each setting icon **111**. The initial set value group is a set of the initial set values corresponding to the individual setting icons **111** and stored as the initial set value group in the memory **17** in advance. The initial set value group is set for each scene type selected on the scene setting screen **100**. The detailed setting screen **110** is an operation screen set for each scene type. The control unit **21** reads out, from the memory **17**, the initial set value group of the scene type corresponding to the detailed setting screen **110** that is displayed. The detailed setting screen **110** is a screen where a change in the initial set value of the setting item corresponding to the setting icon **111** can be accepted. When the first detailed setting screen **110a** is displayed, the control unit **21** reads out the initial set value corresponding to each of the plurality of setting icons **111**. The initial set value group that is read out is an initial game set value group for the game scene, which is the scene type corresponding to the game icon **101a**. The initial game set value group is an example of a plurality of initial set value groups.

The color mode setting icon **111a** is an icon selected when the user sets a color mode. When the user sets the color mode, the user makes an operation input to the color mode setting icon **111a**. As the user makes the operation input to the color mode setting icon **111a**, the color mode setting icon **111a** is selected. The color mode is an item related to the setting of the brightness, contrast, and color balance of the projection image PG. The color mode is a dynamic mode, a vivid mode, a natural mode or the like. In an example, when the game icon **101a** is selected on the first scene setting screen **100a**, the dynamic mode is read out from the memory **17** as the initial set value of the color mode. When the color mode setting icon **111a** is selected, the user can change the dynamic mode, which is the initial set value, to another set value. When the user has changed the initial set value to another set value, the OSD control unit **23** acquires the changed set value as the set value of the color mode. When the user does not change the initial set value, the OSD control unit **23** acquires the initial set value as the set value of the color mode. The color mode setting icon **111a** is equivalent to an example of an item display field. The set value of the color mode is equivalent to an example of an item set value.

The brightness setting icon **111b** is an icon selected when the user sets the brightness of the projection image PG. When the user sets the brightness of the projection image PG, the user makes an operation input to the brightness setting icon **111b**. As the user makes the operation input to the brightness setting icon **111b**, the brightness setting icon **111b** is selected. The brightness of the projection image PG is expressed by a numerical value or the like. When the game icon **101a** is selected on the first scene setting screen **100a**, the initial set value of the brightness included in the initial set value group corresponding to the game scene is read out

12

from the memory **17**. When the brightness setting icon **111b** is selected, the user can change the initial set value of the brightness to another set value. When the user has changed the initial set value to another set value, the OSD control unit **23** acquires the changed set value as the set value of the brightness. When the user does not change the initial set value, the OSD control unit **23** acquires the initial set value as the set value of the brightness. The brightness setting icon **111b** is equivalent to an example of the item display field.

10 The set value of the brightness is equivalent to an example of the item set value.

The contrast setting icon **111c** is an icon selected when the user sets the contrast of the projection image PG. When the user sets the contrast of the projection image PG, the user makes an operation input to the contrast setting icon **111c**. As the user makes the operation input to the contrast setting icon **111c**, the contrast setting icon **111c** is selected. The contrast of the projection image PG is expressed by a numerical value or the like. When the game icon **101a** is selected on the first scene setting screen **100a**, the initial set value of the contrast included in the initial set value group corresponding to the game scene is read out from the memory **17**. When the contrast setting icon **111c** is selected, the user can change the initial set value of the contrast to another set value. When the user has changed the initial set value to another set value, the OSD control unit **23** acquires the changed set value as the set value of the contrast. When the user does not change the initial set value, the OSD control unit **23** acquires the initial set value as the set value of the contrast. The contrast setting icon **111c** is equivalent to an example of the item display field. The set value of the contrast is equivalent to an example of the item set value.

The sharpness setting icon **111d** is an icon selected when the user sets the sharpness of the projection image PG. When the user sets the way the contour of the projection image PG looks, the user makes an operation input to the sharpness setting icon **111d**. As the user makes the operation input to the sharpness setting icon **111d**, the sharpness setting icon **111d** is selected. The sharpness of the projection image PG is expressed by a numerical value or the like. When the game icon **101a** is selected on the first scene setting screen **100a**, the initial set value of the sharpness included in the initial set value group corresponding to the game scene is read out from the memory **17**. When the sharpness setting icon **111d** is selected, the user can change the initial set value to another set value. When the user has changed the initial set value to another set value, the OSD control unit **23** acquires the changed set value as the set value of the sharpness. When the user does not change the initial set value, the OSD control unit **23** acquires the initial set value as the set value of the sharpness. The sharpness setting icon **111d** is equivalent to an example of the item display field. The set value of the sharpness is equivalent to an example of the item set value.

55 The frame delay setting icon **111e** is an icon selected when the user sets the frame delay when displaying the projection image PG. When the user sets the frame delay, the user makes an operation input to the frame delay setting icon **111e**. As the user makes the operation input to the frame delay setting icon **111e**, the frame delay setting icon **111e** is selected. The frame delay to be set is a low delay mode, a high image quality mode or the like. In an example, when the game icon **101a** is selected on the first scene setting screen **100a**, the low delay mode is read out from the memory **17** as the initial set value of the frame delay. When the frame delay setting icon **111e** is selected, the user can change the initial set value to another set value. When the

user has changed the initial set value to another set value, the OSD control unit 23 acquires the changed set value as the set value of the frame delay. When the user does not change the initial set value, the OSD control unit 23 acquires the initial set value as the set value of the frame delay. The frame delay setting icon 111e is equivalent to an example of the item display field. The set value of the frame delay is equivalent to an example of the item set value.

The aspect setting icon 111f is an icon selected when the user sets the aspect ratio of the projection image PG. When the user sets the aspect ratio of the projection image PG, the user makes an operation input to the aspect setting icon 111f. As the user makes the operation input to the aspect setting icon 111f, the aspect setting icon 111f is selected. The aspect ratio to be set is 4:3, 16:10, 16:9 or the like. In an example, when the game icon 101a is selected on the first scene setting screen 100a, the 16:9 is read out from the memory 17 as the initial set value of the aspect ratio. When the aspect setting icon 111f is selected, the user can change the initial set value to another set value. When the user has changed the initial set value to another set value, the OSD control unit 23 acquires the changed set value as the set value of the aspect ratio. When the user does not change the initial set value, the OSD control unit 23 acquires the initial set value as the set value of the aspect ratio. The aspect setting icon 111f is equivalent to an example of the item display field. The set value of the aspect ratio is equivalent to an example of the item set value.

The sound volume setting icon 111g is an icon selected when the user sets the sound volume when displaying the projection image PG. When the user sets the sound volume, the user makes an operation input to the sound volume setting icon 111g. As the user makes the operation input to the sound volume setting icon 111g, the sound volume setting icon 111g is selected. The sound volume is expressed by a numerical value or the like. When the game icon 101a is selected on the first scene setting screen 100a, the initial set value of the sound volume included in the initial set value group corresponding to the game scene is read out from the memory 17. When the sound volume setting icon 111g is selected, the user can change the initial sound volume set value to another set value. When the user has changed the initial set value to another set value, the OSD control unit 23 acquires the changed set value as the set value of the sound volume. When the user does not change the initial set value, the OSD control unit 23 acquires the initial set value as the set value of the sound volume.

FIG. 7 shows a schematic configuration of the detailed setting screen 110. FIG. 7 shows a second detailed setting screen 110b, which is an example of the detailed setting screen 110. The second detailed setting screen 110b is displayed when a selection input to the movie icon 101b is accepted on the first scene setting screen 100a. The second detailed setting screen 110b corresponds to the movie icon 101b. The second detailed setting screen 110b is equivalent to an example of a second display setting screen.

The detailed setting screen 110 corresponding to each of the plurality of selection icons 101 included in the scene setting screen 100 is preset. The detailed setting screens 110 corresponding to the individual selection icons 101 may be configured to have the same display content or may be configured to have different display contents from each other. Preferably, the detailed setting screens 110 corresponding to the selection icons 101 may be configured to have different display contents from each other. The second

detailed setting screen 110b shown in FIG. 7 is in a different display form from the first detailed setting screen 110a shown in FIG. 6.

The second detailed setting screen 110b displays a plurality of setting icons 111. The second detailed setting screen 110b displays a color mode setting icon 111a, a brightness setting icon 111b, a contrast setting icon 111c, a sharpness setting icon 111d, a frame delay setting icon 111e, an aspect setting icon 111f, and a sound volume setting icon 111g. The 10 plurality of setting icons 111 displayed on the second detailed setting screen 110b are the same as the plurality of setting icons 111 displayed on the first detailed setting screen 110a and have the same functions.

The color mode setting icon 111a, the contrast setting icon 15 111c, and the aspect setting icon 111f included in the second detailed setting screen 110b are displayed in a different display form from the setting icons 111 included in the first detailed setting screen 110a. The color mode setting icon 111a, the contrast setting icon 111c, and the aspect setting 20 icon 111f included in the second detailed setting screen 110b are highlighted. The color mode setting icon 111a, the contrast setting icon 111c, and the aspect setting icon 111f are the setting icons 111 related to items whose initial set value is likely to be changed by the user. As a predetermined 25 setting icon 111 of the plurality of setting icons 111 is highlighted, the user can more easily check the highlighted setting icon 111.

The second detailed setting screen 110b shown in FIG. 7 is configured to have a different display form from the first 30 detailed setting screen 110a shown in FIG. 6 but is not limited to this configuration. The second detailed setting screen 110b may be configured to have a different display order from the display order of the plurality of setting icons 111 in the first detailed setting screen 110a.

The control unit 21 reads out, from the memory 17, the initial set value corresponding to the setting icon 111 displayed on the detailed setting screen 110. The control unit 21 reads out, from the memory 17, the initial set value group including the initial set value corresponding to each setting 40 icon 111. When the second detailed setting screen 110b is displayed, the control unit 21 reads out the initial set value group including the initial set value corresponding to each of the plurality of setting icons 111. The initial set value group that is read out is the initial set value group of the movie scene, which is the scene type corresponding to the movie 45 icon 101b.

Referring back to FIG. 4, after displaying the detailed setting screen 110, the projector 10 in step S113 accepts a set value corresponding to the setting icon 111. The user makes 50 an operation input to one setting icon 111, of the plurality of setting icons 111 included in the detailed setting screen 110. The OSD control unit 23 accepts the operation input to the one setting icon 111. When the one setting icon 111 is selected, the user can change the initial set value of the 55 setting item corresponding to the one setting icon 111 to another set value. When the user has changed the initial set value to another set value, the OSD control unit 23 acquires the changed set value as the set value of the setting item. When the user does not change the initial set value, the OSD 60 control unit 23 acquires the initial set value as the set value of the setting item.

When the user has made an operation input to the decision button, which is the input button 13 included in the operation panel 11, the OSD control unit 23 acquires the set value of the setting item corresponding to the setting icon 111. When the user has changed the set values of setting items corresponding to a plurality of setting icons 111, the OSD control 65

15

unit 23 acquires a set value group formed of a set of the set values of the plurality of setting items. The OSD control unit 23 outputs the acquired set value group to the image control unit 25.

After accepting the set value, the projector 10 in step S115 corrects the image data and displays the corrected image data that is corrected. The image control unit 25 acquires the set value group from the OSD control unit 23. The image control unit 25 corrects the image data, using the set value group. The image control unit 25 outputs the image data that is corrected, as corrected image data, to the projection unit 30. The projection unit 30 projects the projection image PG onto the projection surface SC, based on the corrected image data. The image control unit 25 causes the projection unit 30 to project the projection image PG based on the corrected image data and thus to display the projection image PG on the projection surface SC.

In FIG. 4, the detailed setting screen 110 is displayed in step S111 after the mode information is stored in step S109. However, this configuration is not limiting. When a selection input to the selection icon 101 is accepted, the OSD control unit 23 may acquire the initial set value group corresponding to the selected scene type and may output the initial set value group to the image control unit 25. The image control unit 25 corrects the image data, using the acquired initial set value group. The image control unit 25 causes the projection unit 30 to project the projection image PG, based on the corrected image data that is corrected.

The display method includes: presetting the screen display mode for displaying the scene setting screen 100; accepting an input of image data from the image providing device 50; and displaying the scene setting screen 100, when the image data is inputted and it is determined that the image display mode is in operation.

Since the screen display mode is preset, the scene setting screen 100 is displayed regardless of the scene type of the image data when the image data is inputted. The user of the projector 10 can recognize that a setting related to image adjustment can be made. The projector 10 can display the scene setting screen 100 to a user who is not very familiar with user settings.

The display method includes: not displaying the scene setting screen 100 when the image data is inputted after the screen display mode is switched to the screen non-display mode.

If the screen non-display mode is set as the mode information when the scene setting screen 100 is displayed, the scene setting screen 100 is not displayed the next time the user inputs the image data from the image providing device 50. The user need not check the scene setting screen 100 every time the user inputs the image data from the image providing device 50.

The first scene setting screen 100a includes the game icon 101a and the movie icon 101b. The display method includes: displaying the first detailed setting screen 110a corresponding to the game icon 101a when a selection input to the game icon 101a is accepted; and displaying the second detailed setting screen 110b corresponding to the movie icon 101b when a selection input to the movie icon 101b is accepted.

The detailed setting screen 110 for each selected selection icon 101 is displayed. The user can set the set values of various setting items, using the detailed setting screen 110 for each scene type.

The first detailed setting screen 110a includes the setting icon 111 related to image adjustment. The display method includes: accepting the set value corresponding to the setting icon 111 when the first detailed setting screen 110a is

16

displayed; and displaying the projection image PG based on the image data corrected based on the set value.

The image correction of the projection image PG can be made, based on the set value inputted using the first detailed setting screen 110a.

The projector 10 has: the communication interface 15 accepting an input of image data outputted from the image providing device 50; the control unit 21 executing presetting the screen display mode for displaying the scene setting screen 100, and displaying the scene setting screen 100, when the image data is inputted to the communication interface 15 and it is determined that the screen display mode is in operation; and the projection unit 30 displaying the scene setting screen 100 under the control of the control unit 21.

Since the screen display mode is preset, the scene setting screen 100 is displayed regardless of the scene type of the image data when the image data is inputted. The projector 10 can display the scene setting screen 100 to a user who is not very familiar with user settings. The user of the projector 10 can recognize that a setting related to image adjustment can be made.

The operation panel 11 or the remote controller for accepting an operation to set the screen non-display mode for not displaying the scene setting screen when the projection unit 30 displays the scene setting screen 100, is provided.

The user, using the operation panel 11 or the remote controller, can select the screen non-display mode for not displaying the scene setting screen 100 when the image data is inputted.

Second Embodiment

35 A second embodiment represents a display method for displaying a scene setting screen 100 that is different from the scene setting screen 100 in the first embodiment. The second embodiment represents a display method for displaying a second scene setting screen 100b, which is an example of the scene setting screen 100.

FIG. 8 shows a schematic configuration of the scene setting screen 100. FIG. 8 shows a schematic configuration of the second scene setting screen 100b, which is an example of the scene setting screen 100. The display content of the 45 second scene setting screen 100b is different from the display content of the first scene setting screen 100a.

The second scene setting screen 100b displays a plurality of selection icons 101. Each of the plurality of selection icons 101 can accept a selection input, which is an operation input by the user. The user makes an operation input to the input button 13 on the operation panel 11 and thus can select a selection icon 101. The plurality of selection icons 101 are a game icon 101a, a movie icon 101b, a presentation icon 101c, a multi-screen icon 101d, a common icon 101e, and an 50 icon yet to be set 101f. The plurality of selection icons 101 displayed on the second scene setting screen 100b are the same as the plurality of selection icons 101 displayed on the first scene setting screen 100a. The plurality of selection icons 101 displayed on the second scene setting screen 100b may be the same as or different from the plurality of selection icons 101 displayed on the first scene setting screen 100a. The number of the selection icons 101 displayed on the second scene setting screen 100b is not limited to six. The number of the selection icons 101 may be any 55 number equal to or greater than two.

The second scene setting screen 100b displays a display setting field 103. The display setting field 103 accepts a

switching operation input to switch from the screen display mode to the screen non-display mode. The screen non-display mode can be set when the second scene setting screen **100b** is displayed. The display setting field **103** displayed on the second scene setting screen **100b** is the same as the display setting field **103** displayed on the first scene setting screen **100a**. The display setting field **103** illustrated in FIG. 8 shows a state where no switching operation input is accepted. When the switching operation input to the display setting field **103** is accepted, the display form of the display setting field **103** is changed. In an example, a checkmark image is superimposed on the display setting field **103**.

The second scene setting screen **100b** displays an automatic selection field **105**. The automatic selection field **105** accepts a change input to apply an automatic scene setting in which the control unit **21** automatically adjusts the projection image PG. The automatic scene setting is equivalent to an example of an automatic setting. The automatic scene setting can be set when the second scene setting screen **100b** is displayed. The user switches whether to apply the automatic scene setting or not, using the automatic selection field **105**. When the user has made a change input to apply the automatic scene setting to the automatic selection field **105**, the control unit **21** accepts the change input. The automatic selection field **105** illustrated in FIG. 8 shows a state where no change input is accepted. When the change input to the automatic selection field **105** is accepted, the display form of the automatic selection field **105** is changed. In an example, a checkmark image is superimposed on the automatic selection field **105**. The automatic selection field **105** is equivalent to an example of an automatic setting field. The change input is equivalent to an example of automatic setting information.

FIG. 9 shows a flowchart related to a display method for the projector **10**. FIG. 9 shows a display method for displaying the second scene setting screen **100b**, which is an example of the scene setting screen **100**.

In step S201, the projector **10** takes in image data inputted from the image providing device **50**. The communication interface **15** of the projector **10** communicatively connects to the communication unit **57** of the image providing device **50**. The communication interface **15** takes in image data inputted from the communication unit **57**. The communication interface **15** outputs the image data to the OSD control unit **23** of the control unit **21**. The OSD control unit **23** takes in the image data inputted thereto.

When the image data is inputted to the projector **10**, the projector **10** determines in step S203 whether the mode information represents the screen display mode or not. The mode information represents the screen display mode or the screen non-display mode. The mode information is preset before the image data is inputted. The mode information is stored in the memory **17**. In initial settings, the screen display mode is preset in the projector **10**.

When it is determined that the mode information represents the screen display mode, the OSD control unit **23** proceeds to step S205 (YES in step S203). When it is determined that the mode information does not represent the screen display mode, the OSD control unit **23** determines that the mode information represents the screen non-display mode. When it is determined that the mode information represents the screen non-display mode, the OSD control unit **23** proceeds to step S221 (NO in step S203).

In step S205, the projector **10** displays the second scene setting screen **100b**. The OSD control unit **23** causes the projection unit **30** to project the second scene setting screen

100b, based on the scene setting screen data, and thus to display the second scene setting screen **100b** on the projection surface SC. The projection unit **30** projects the second scene setting screen **100b** onto the projection surface SC under the control of the OSD control unit **23**.

After displaying the second scene setting screen **100b**, the projector **10** in step S207 accepts a selection input from the user. The user operates the input button **13** on the operation panel **11** and thus makes a selection input. A selection input to one selection icon **101** of the plurality of selection icons **101** displayed on the second scene setting screen **100b** shown in FIG. 8 is accepted. A switching operation input by the user to the display setting field **103** may be accepted. Also, a change input by the user to the automatic selection field **105** may be accepted.

When the change input to the automatic selection field **105** is accepted, the display form of the display setting field **103** may be changed. When the change input to the automatic selection field **105** is accepted, the display setting field **103** is changed to the display form as of when the switching operation input is accepted. The change input to the automatic selection field **105** includes the switching operation input to the display setting field **103**. The change input to the automatic selection field **105** is linked to the switching operation input to the display setting field **103**.

When the operation input to the selection icon **101** is accepted, the projector **10** in step S209 accepts a scene type corresponding to the selection icon **101** accepted on the second scene setting screen **100b**. The OSD control unit **23** accepts the scene type corresponding to selection icon **101**. The OSD control unit **23** temporarily stores the scene type corresponding to the selection icon **101**. The OSD control unit **23** may cause the memory **17** to store the scene type corresponding to the selection icon **101**.

When the switching operation input to the display setting field **103** is accepted, the projector **10** in step S209 switches from the screen display mode to the screen non-display mode. The OSD control unit **23** causes the memory **17** to store the screen non-display mode as the mode information, based on the switching operation input. When no switching operation input to the display setting field **103** is accepted, the projector **10** in step S209 does not switch the mode information from the screen display mode to the screen non-display mode. The projector **10** maintains the screen display mode. The memory **17** continues storing the screen display mode as the mode information.

When the change input to the automatic selection field **105** is accepted, the projector **10** in step S209 changes to the automatic scene setting. The OSD control unit **23** causes the memory **17** to store the automatic scene setting, based on the change input. When the change input to the automatic selection field **105** is accepted, the projector **10** switches the mode information from the screen display mode to the screen non-display mode. The OSD control unit **23** causes the memory **17** to store the screen non-display mode as the mode information, based on the change input. When no change input to the automatic selection field **105** is accepted, the projector **10** in step S209 does not change to the automatic scene setting.

After storing the scene type corresponding to the selection icon **101**, the projector **10** in step S211 displays the detailed setting screen **110**. The OSD control unit **23** transmits the detailed setting screen data to the projection unit **30**. The OSD control unit **23** causes the detailed setting screen **110** to be projected onto the projection surface SC, based on the detailed setting screen data. The OSD control unit **23** causes the projection unit **30** to project the detailed setting screen

110 and thus to display the detailed setting screen 110 on the projection surface SC. The detailed setting screen 110 that is displayed is the first detailed setting screen 110a shown in FIG. 6, or the like.

After displaying the detailed setting screen 110, the projector 10 in step S213 accepts a set value corresponding to the setting icon 111. The user makes an operation input to one setting icon 111, of the plurality of setting icons 111 included in the detailed setting screen 110. The OSD control unit 23 accepts the operation input to the one setting icon 111. When the one setting icon 111 is selected, the user can change the initial set value of the setting item corresponding to the one setting icon 111 to another set value. When the user has changed the initial set value to another set value, the OSD control unit 23 acquires the changed set value as the set value of the setting item. When the user does not change the initial set value, the OSD control unit 23 acquires the initial set value as the set value of the setting item.

When the user has made an operation input to the decision button, which is the input button 13 included in the operation panel 11, the OSD control unit 23 acquires the set value of the setting item corresponding to the setting icon 111. When the user has changed the set values of setting items corresponding to a plurality of setting icons 111, the OSD control unit 23 acquires a set value group formed of a set of the set values of the plurality of setting items. The OSD control unit 23 outputs the acquired set value group to the image control unit 25.

After accepting the set value, the projector 10 in step S215 corrects the image data and displays the corrected image data that is corrected. The image control unit 25 acquires the set value group from the OSD control unit 23. The image control unit 25 corrects the image data, using the set value group. The image control unit 25 outputs the image data that is corrected, as corrected image data, to the projection unit 30. The projection unit 30 projects the projection image PG onto the projection surface SC, based on the corrected image data. The image control unit 25 causes the projection unit 30 to project the projection image PG based on the corrected image data and thus to display the projection image PG on the projection surface SC.

In FIG. 9, the detailed setting screen 110 is displayed in step S211 after the mode information is stored in step S209. However, this configuration is not limiting. When a selection input to the selection icon 101 is accepted, the OSD control unit 23 may acquire the initial set value group corresponding to the selected scene type and may output the initial set value group to the image control unit 25. The image control unit 25 corrects the image data, using the acquired initial set value group. The image control unit 25 causes the projection unit 30 to project the projection image PG, based on the corrected image data that is corrected.

When it is determined in step S203 that the mode information represents the screen non-display mode, the projector 10 proceeds to step S221 (NO in step S203). In step S221, the projector 10 determines whether the automatic scene setting is applied or not. When it is determined that the automatic scene setting is stored in the memory 17, the control unit 21 proceeds to step S223 (SET in step S221). When it is determined that the automatic scene setting is not stored in the memory 17, the control unit 21 proceeds to step S231 (NOT SET in step S221).

In step S223, the projector 10 determines the scene type of the image data. The control unit 21 analyzes the image data and thus determines the scene type based on the image data. The control unit 21 analyzes an image pattern or the like included in the image data and thus determines the scene

type. The scene type is game, movie, presentation, multi-screen or the like. The scene type is equivalent to an example of an image type.

After determining the scene type, the projector 10 in step S225 acquires a set value group. The OSD control unit 23 acquires the initial set value group that is set or each scene type stored in the memory 17. The memory 17 stores the initial set value group corresponding to the scene type. The memory 17 stores the initial set value group corresponding to the game scene, the initial set value group corresponding to the movie scene, and the like. The OSD control unit 23 acquires the initial set value group and outputs the initial set value group as a set value group to the image control unit 25. The projector 10 proceeds to step S215.

When it is determined in step S221 that the automatic scene setting is not applied, the projector 10 proceeds to step S231 (NOT SET in step S221). In step S231, the projector 10 acquires a standard set value group. The OSD control unit 23 reads out the standard set value group from the memory 17. The OSD control unit 23 outputs the standard set value group as a set value group to the image control unit 25. The projector 10 proceeds to step S215.

The second scene setting screen 100b has the automatic selection field 105 for switching whether or not to apply the automatic scene setting to automatically adjust the projection image PG displayed based on the image data. The display method includes: accepting a change input to the automatic selection field 105 when the second scene setting screen 100b is displayed; and switching the screen display mode to the screen non-display mode when the change input indicates that the automatic scene setting is to be applied.

When the automatic scene setting is applied, the second scene setting screen 100b is not displayed. When the automatic scene setting is applied, the user may not view the second scene setting screen 100b.

The display method further includes determining the scene type based on the image data, when the image data is inputted and it is determined that the automatic scene setting is applied.

When the automatic scene setting is applied, the scene type based on the image data is determined. Therefore, the set value group corresponding to the scene type can be set.

Third Embodiment

A third embodiment represents a display method that is different from the display methods in the first and second embodiments. The third embodiment represents a display method for the projector 10 in which the external device information 19 of the image providing device 50 and the mode information are stored in association with each other. The external device information 19 corresponds to the device-specific information 53 of the image providing device 50. FIG. 10 shows a flowchart related to a display method for the projector 10. FIG. 10 shows a display method for the projector 10 in which the external device information 19 of the image providing device 50 and the mode information are stored in association with each other.

In step S301, the projector 10 takes in image data and the device-specific information 53 inputted from the image providing device 50. The communication interface 15 of the projector 10 communicatively connects to the communication unit 57 of the image providing device 50. The communication interface 15 takes in image data and the device-specific information 53 inputted from the communication unit 57. The device-specific information 53 is added to the image data and thus outputted from the image providing

device **50**. When communicatively connected to the projector **10**, the image providing device **50** may output the device-specific information **53** separately from the image data to the projector **10**. The communication interface **15** outputs the image data to the OSD control unit **23** of the control unit **21**. The OSD control unit **23** takes in the image data inputted thereto.

After taking in the image data and the device-specific information **53**, the projector **10** in step S302 determines whether the external device information **19** corresponding to the device-specific information **53** is stored in the memory **17** or not. The memory **17** stores the external device information **19** and the mode information in association with each other. The memory **17** stores the external device information **19** and the screen display mode in association with each other. Alternatively, the memory **17** stores the external device information **19** and the screen non-display mode in association with each other. When the device-specific information **53** is inputted to the communication interface **15**, the memory **17** stores the external device information **19** as information corresponding to the device-specific information **53**. When the image providing device **50** outputs image data to the projector **10** for the first time, the memory **17** stores the external device information **19** corresponding to the device-specific information **53**, and the screen display mode, which is the initial setting, in association with each other. When the user sets the screen non-display mode using the scene setting screen **100**, the memory **17** stores the external device information **19** corresponding to the device-specific information **53** of the image providing device **50** outputting the image data, and the screen non-display mode, in association with each other.

The OSD control unit **23** determines whether the external device information **19** corresponding to the device-specific information **53** is stored in the memory **17** or not. When the external device information **19** is not stored in the memory **17**, the OSD control unit **23** proceeds to step S305 (NO in step S302). When the image providing device **50** outputs image data to the projector **10** for the first time, the external device information **19** corresponding to the device-specific information **53** is not stored in the memory **17**. After the memory **17** stores the external device information **19** and the screen display mode in association with each other, the projector **10** proceeds to step S305. When the external device information **19** corresponding to the device-specific information **53** is stored in the memory **17**, the OSD control unit **23** proceeds to step S303 (YES in step S302).

When it is determined that the external device information **19** is stored, the projector **10** in step S303 determines whether the mode information associated with the external device information **19** is the screen display mode or not. Once the image providing device **50** is connected to the projector **10**, the external device information **19** corresponding to the device-specific information **53** is stored in the memory **17**. When it is determined that the external device information **19** and the screen display mode are stored in association with each other in the memory **17**, the OSD control unit **23** proceeds step S305 (YES in step S303). When it is determined that the external device information **19** and the screen non-display mode are stored in association with each other in the memory **17**, the OSD control unit **23** proceeds to step S331 (NO in step S303). When proceeding to step S331, the OSD control unit **23** does not display the first scene setting screen **100a**.

When it is determined in step S303 that the mode information represents the screen non-display mode, the projector **10** acquires a standard set value group in step S331. The

OSD control unit **23** reads out the standard set value group from the memory **17**. The OSD control unit **23** outputs the standard set value group as a set value group to the image control unit **25**. The projector **10** proceeds to step S315.

5 In step S305, the projector **10** displays the first scene setting screen **100a**. The OSD control unit **23** causes the projection unit **30** to project the first scene setting screen **100a**, based on the scene setting screen data, and thus to display the first scene setting screen **100a** on the projection 10 surface SC. The projection unit **30** projects the first scene setting screen **100a** onto the projection surface SC under the control of the OSD control unit **23**. The projector **10** in step S305 displays the first scene setting screen **100a** but is not limited to this. The projector **10** may display the second 15 scene setting screen **100b**.

After displaying the first scene setting screen **100a**, the projector **10** in step S307 accepts a selection input from the user. The user operates the input button **13** on the operation panel **11** and thus makes a selection input. A selection input 20 to one selection icon **101** of the plurality of selection icons **101** displayed on the first scene setting screen **100a** shown in FIG. 5 is accepted. A switching operation input by the user to the display setting field **103** may be accepted.

When the selection input to the selection icon **101** is 25 accepted, the projector **10** in step S309 accepts a scene type corresponding to the selection icon **101** accepted on the first scene setting screen **100a**. The OSD control unit **23** accepts the scene type corresponding to selection icon **101**. The OSD control unit **23** temporarily stores the scene type 30 corresponding to the selection icon **101**. The OSD control unit **23** may cause the memory **17** to store the scene type corresponding to the selection icon **101**.

When the switching operation input to the display setting field **103** is accepted, the projector **10** in step S309 switches 35 from the screen display mode to the screen non-display mode. The OSD control unit **23** causes the memory **17** to store the screen non-display mode as the mode information, based on the switching operation input.

After storing the scene type corresponding to the selection 40 icon **101**, the projector **10** in step S311 displays the detailed setting screen **110**. The OSD control unit **23** transmits the detailed setting screen data to the projection unit **30**. The OSD control unit **23** causes the detailed setting screen **110** to be projected onto the projection surface SC, based on the 45 detailed setting screen data. The OSD control unit **23** causes the projection unit **30** to project the detailed setting screen **110** and thus to display the detailed setting screen **110** on the projection surface SC.

After displaying the detailed setting screen **110**, the projector **10** in step S313 accepts a set value corresponding to the setting icon **111**. The user makes an operation input to one setting icon **111**, of the plurality of setting icons **111** included in the detailed setting screen **110**. The OSD control unit **23** accepts the operation input to the one setting icon 50 **111**. When the one setting icon **111** is selected, the user can change the initial set value of the setting item corresponding to the one setting icon **111** to another set value. When the user has changed the initial set value to another set value, the OSD control unit **23** acquires the changed set value as the set 55 value of the setting item. When the user does not change the initial set value, the OSD control unit **23** acquires the initial set value as the set value of the setting item.

When the user has made an operation input to the decision button, which is the input button **13** included in the operation 60 panel **11**, the OSD control unit **23** acquires the set value of the setting item corresponding to the setting icon **111**. When the user has changed the set values of setting items corre-

23

sponding to a plurality of setting icons 111, the OSD control unit 23 acquires a set value group formed of a set of the set values of the plurality of setting items. The OSD control unit 23 outputs the acquired set value group to the image control unit 25.

After accepting the set value, the projector 10 in step S315 corrects the image data and displays the corrected image data that is corrected. The image control unit 25 acquires the set value group from the OSD control unit 23. The image control unit 25 corrects the image data, using the set value group. The image control unit 25 outputs the image data that is corrected, as corrected image data, to the projection unit 30. The projection unit 30 projects the projection image PG onto the projection surface SC, based on the corrected image data. The image control unit 25 causes the projection unit 30 to project the projection image PG based on the corrected image data and thus to display the projection image PG on the projection surface SC.

In FIG. 10, the detailed setting screen 110 is displayed in step S311 after the mode information is stored in step S309. However, this configuration is not limiting. When a selection input to the selection icon 101 is accepted, the OSD control unit 23 may acquire the initial set value group corresponding to the selected scene type and may output the initial set value group to the image control unit 25. The image control unit 25 corrects the image data, using the acquired initial set value group. The image control unit 25 causes the projection unit 30 to project the projection image PG, based on the corrected image data that is corrected.

The image data includes the device-specific information 53 identifying the image providing device 50. The display method includes: storing the screen display mode or the screen non-display mode in association with the external device information 19 corresponding to the device-specific information 53; acquiring the device-specific information 53 included in the image data, when the image data is inputted; and displaying the scene setting screen 100 when it is determined that the device-specific information 53 does not correspond to the external device information 19.

When image data is inputted to the projector 10 from the image providing device 50 that has never been connected thereto, the scene setting screen 100 is displayed. The scene setting screen 100 is displayed to a user using the projector 10 for the first time. The user checks the scene setting screen 100 and thus can recognize that various settings can be made.

The display method includes: in the case where it is determined that the device-specific information 53 corresponds to the external device information 19, displaying the scene setting screen 100 when it is determined that the mode information associated with the external device information 19 represents the screen display mode; and not displaying the scene setting screen 100 when it is determined that the mode information represents the screen non-display mode.

The display or non-display of the scene setting screen 100 corresponding to the stored mode information is performed with respect to the image providing device 50 having previously outputted image data to the projector 10. Whether to display the scene setting screen 100 or not can be set for each image providing device 50.

In the embodiments of the present disclosure, a configuration using the projector 10 as a display device is described. However, this configuration is not limiting. Another display device having a display panel for displaying an image may be employed. For example, the display device may be a liquid crystal display device that displays an image on a liquid crystal display panel, a display device that displays an

24

image on an organic EL (electroluminescence) panel, or a self-light-emitting display device such as a monitor, a liquid crystal television or a flat panel display.

A summary of the present disclosure is given below in the form of supplementary notes.

Supplementary Note 1

A display method according to the present disclosure includes: presetting a display mode for displaying a setting screen; accepting an input of an image signal from an external device; and displaying the setting screen, when the image signal is inputted and it is determined that the display mode is in operation.

Since the display mode is preset, the setting screen is displayed regardless of the type of the image signal when the image signal is inputted. A display device can display the setting screen to a user who is not very familiar with user settings. The user of the display device can recognize that a setting related to image adjustment can be made.

Supplementary Note 2

As a display method according to the present disclosure, the display method according to Supplementary Note 1 further includes: accepting an operation to set a non-display mode for not displaying the setting screen, when the setting screen is displayed.

The non-display mode can be selected when the image signal is inputted. When the image signal is inputted to the display device, the user can switch to the non-display mode for not displaying the setting screen.

Supplementary Note 3

As a display method according to the present disclosure, in the display method according to Supplementary Note 2, the setting screen has a switching input field for accepting an operation to switch from the display mode to the non-display mode, and accepting the operation to set the non-display mode for not displaying the setting screen includes: accepting switching input information inputted to the switching input field when the setting screen is displayed; and switching the display mode to the non-display mode, based on the switching input information.

The non-display mode can be set when the setting screen is displayed. The user can select not to display the setting screen the next time the image signal is inputted from the external device.

Supplementary Note 4

As a display method according to the present disclosure, the display method according to Supplementary Note 3 further includes: not displaying the setting screen when the image signal is inputted after the switching to the non-display mode is made.

If the non-display mode is set as the mode information when the setting screen is displayed, the setting screen is not displayed the next time the user inputs the image signal from the external device. The user need not check the setting screen every time the user inputs the image signal from the external device.

Supplementary Note 5

As a display method according to the present disclosure, in the display method according to one of Supplementary

25

Notes 2 to 4, the image signal includes an identification signal that identifies the external device. The display method further includes: storing the display mode or the non-display mode in association with identification information corresponding to the identification signal; acquiring the identification signal included in the image signal, when the image signal is inputted; and displaying the setting screen when it is determined that the identification signal does not correspond to the identification information.

When the image signal is inputted to the display device from the external device that has never been connected thereto, the setting screen is displayed. The setting screen is displayed to a user using the display device for the first time. The user checks the setting screen and thus can recognize that various settings can be made.

Supplementary Note 6

As a display method according to the present disclosure, the display method according to Supplementary Note 5 further includes: in the case where it is determined that the identification signal corresponds to the identification information, displaying the setting screen when it is determined that a mode associated with the identification information is the display mode; and not displaying the setting screen when it is determined that the mode associated with the identification information is the non-display mode.

The display or non-display of the setting screen corresponding to a stored display condition is performed with respect to the external device that has previously outputted the image signal to the display device. Whether to display the setting screen or not can be set for each external device.

Supplementary Note 7

As a display method according to the present disclosure, in the display method according to one of Supplementary Notes 2 to 6, the setting screen has an automatic setting field for switching whether or not to apply an automatic setting to automatically adjust an image displayed based on the image signal. The display method includes: accepting automatic setting information inputted to the automatic setting field when the setting screen is displayed; and switching the display mode to the non-display mode when the automatic setting information indicates that the automatic setting is to be applied.

When the automatic setting is applied, the setting screen is not displayed. When the automatic setting is set, the user may not view the setting screen.

Supplementary Note 8

As a display method according to the present disclosure, the display method according to Supplementary Note 7 further includes: determining an image type based on the image signal, when the image signal is inputted and it is determined that the automatic setting is applied.

When the automatic setting is set, the image type based on the image signal is determined. Therefore, a set value group corresponding to the image type can be set.

Supplementary Note 9

As a display method according to the present disclosure, in the display method according to one of Supplementary Notes 1 to 8, the setting screen includes a first item image and a second item image. The display method further

26

includes: displaying a first display setting screen corresponding to the first item image when a selection input to the first item image is accepted; and displaying a second display setting screen corresponding to the second item image when the selection input to the second item image is accepted.

The first display setting screen corresponding to the first item image that is selected is displayed. The user can set various set values, using the first display setting screen.

Supplementary Note 10

As a display method according to the present disclosure, in the display method according to Supplementary Note 9, the first display setting screen includes an item display field related to image adjustment. The display method includes: accepting an item set value corresponding to the item display field when the first display setting screen is displayed; and displaying an image based on the image signal corrected based on the item set value.

The image correction of the image can be made, based on the set value inputted using the first display setting screen.

Supplementary Note 11

A display device according to the present disclosure includes: an interface circuit that accepts an input of an image signal outputted from an external device; one or a plurality of processors that execute presetting a display mode for displaying a setting screen, and displaying the setting screen, when the image signal is inputted to the interface circuit and it is determined that the display mode is in operation; and a display panel that displays the setting screen under control of the one or plurality of processors.

Since the display mode is preset, the setting screen is displayed regardless of the type of the image signal when the image signal is inputted. The display device can display the setting screen to a user who is not very familiar with user settings. The user of the display device can recognize that a setting related to image adjustment can be made.

Supplementary Note 12

As a display device according to the present disclosure, the display device according to Supplementary Note 11 has an operation panel or a remote controller that accepts an operation to set a non-display mode for not displaying the setting screen when the display panel displays the setting screen.

The user, using the operation panel or the remote controller, can select the non-display mode for not displaying the setting screen when the image signal is inputted. The user can set the mode for not displaying the setting screen when the image signal is inputted.

What is claimed is:

1. A display method comprising:
presetting a display mode for displaying a setting screen;
accepting an input of an image signal from an external device;
displaying the setting screen, when the image signal is inputted and it is determined that the display mode is in operation; and
accepting an operation to set a non-display mode for not displaying the setting screen, when the setting screen is displayed, wherein
the image signal includes an identification signal that identifies the external device, and
the display method further comprises:

27

storing the display mode or the non-display mode in association with identification information corresponding to the identification signal; acquiring the identification signal included in the image signal, when the image signal is inputted; and displaying the setting screen when it is determined that the identification signal does not correspond to the identification information.

2. The display method according to claim 1, wherein the setting screen has a switching input field for accepting an operation to switch from the display mode to the non-display mode, and accepting the operation to set the non-display mode for not displaying the setting screen comprises: accepting switching input information inputted to the switching input field when the setting screen is displayed; and switching the display mode to the non-display mode, based on the switching input information.

3. The display method according to claim 2, further comprising: not displaying the setting screen when the image signal is inputted after switching to the non-display mode is made.

4. The display method according to claim 1, further comprising: in the case where it is determined that the identification signal corresponds to the identification information, displaying the setting screen when it is determined that a mode associated with the identification information is the display mode; and not displaying the setting screen when it is determined that the mode associated with the identification information is the non-display mode.

5. The display method according to claim 1, wherein the setting screen has an automatic setting field for switching whether or not to apply an automatic setting to automatically adjust an image displayed based on the image signal, and

- the display method comprises: accepting automatic setting information inputted to the automatic setting field when the setting screen is displayed; and switching the display mode to the non-display mode when the automatic setting information indicates that the automatic setting is to be applied.

6. The display method according to claim 5, further comprising: determining an image type based on the image signal, when the image signal is inputted and it is determined that the automatic setting is applied.

7. The display method according to claim 1, wherein the setting screen includes a first item image and a second item image, and

- the display method further comprises: displaying a first display setting screen corresponding to the first item image when a selection input to the first item image is accepted; and displaying a second display setting screen corresponding to the second item image when the selection input to the second item image is accepted.

8. The display method according to claim 7, wherein the first display setting screen includes an item display field related to image adjustment, and

28

the display method comprises: accepting an item set value corresponding to the item display field when the first display setting screen is displayed; and displaying an image based on the image signal corrected based on the item set value.

9. A display device comprising: an interface circuit that accepts an input of an image signal outputted from an external device; one or a plurality of processors that execute presetting a display mode for displaying a setting screen, and displaying the setting screen, when the image signal is inputted to the interface circuit and it is determined that the display mode is in operation; and a display panel that displays the setting screen under control of the one or plurality of processors, wherein the image signal includes an identification signal that identifies the external device, and the one or a plurality of processors further execute accepting an operation to set a non-display mode for not displaying the setting screen, when the setting screen is displayed; storing the display mode or the non-display mode in association with identification information corresponding to the identification signal; acquiring the identification signal included in the image signal, when the image signal is inputted; and displaying the setting screen when it is determined that the identification signal does not correspond to the identification information.

10. The display device according to claim 9, comprising: an operation panel or a remote controller that accepts an operation to set a non-display mode for not displaying the setting screen when the display panel displays the setting screen.

11. The display device according to claim 9, wherein the setting screen has a switching input field for accepting an operation to switch from the display mode to the non-display mode, and accepting the operation to set the non-display mode for not displaying the setting screen comprises:

- accepting switching input information inputted to the switching input field when the setting screen is displayed; and switching the display mode to the non-display mode, based on the switching input information.

12. The display device according to claim 11, further comprising: not displaying the setting screen when the image signal is inputted after switching to the non-display mode is made.

13. The display device according to claim 9, further comprising: the one or a plurality of processors further execute, in the case where it is determined that the identification signal corresponds to the identification information, displaying the setting screen when it is determined that a mode associated with the identification information is the display mode; and not displaying the setting screen when it is determined that the mode associated with the identification information is the non-display mode.

14. The display device according to claim 11, wherein the setting screen includes a first item image and a second item image, and

29

the one or a plurality of processors further execute:
 displaying a first display setting screen corresponding to the first item image when a selection input to the first item image is accepted; and
 displaying a second display setting screen corresponding to the second item image when the selection input to the second item image is accepted.

15. A display method comprising:

presetting a display mode for displaying a setting screen;
 accepting an input of an image signal from an external device;
 displaying the setting screen, when the image signal is inputted and it is determined that the display mode is in operation; and
 accepting an operation to set a non-display mode for not displaying the setting screen, when the setting screen is displayed, wherein
 the setting screen has an automatic setting field for switching whether or not to apply an automatic setting to automatically adjust an image displayed based on the image signal, and

the display method comprises:

accepting automatic setting information inputted to the automatic setting field when the setting screen is displayed; and
 switching the display mode to the non-display mode when the automatic setting information indicates that the automatic setting is to be applied.

16. The display method according to claim 15, wherein

the setting screen has a switching input field for accepting an operation to switch from the display mode to the non-display mode, and
 accepting the operation to set the non-display mode for not displaying the setting screen comprises:

30

accepting switching input information inputted to the switching input field when the setting screen is displayed; and
 switching the display mode to the non-display mode, based on the switching input information.

17. The display method according to claim 16, further comprising:

not displaying the setting screen when the image signal is inputted after switching to the non-display mode is made.

18. The display method according to claim 15, further comprising:

determining an image type based on the image signal, when the image signal is inputted and it is determined that the automatic setting is applied.

19. The display method according to claim 15, wherein

the setting screen includes a first item image and a second item image, and

the display method further comprises:

displaying a first display setting screen corresponding to the first item image when a selection input to the first item image is accepted; and

displaying a second display setting screen corresponding to the second item image when the selection input to the second item image is accepted.

20. The display method according to claim 19, wherein

the first display setting screen includes an item display field related to image adjustment, and

the display method comprises:

accepting an item set value corresponding to the item display field when the first display setting screen is displayed; and

displaying an image based on the image signal corrected based on the item set value.
